UNITED STATES PATENT OFFICE

JAMES L. GETAZ, OF MARYVILLE, TENNESSEE, ASSIGNOR TO SCOTT & WILLIAMS, INC.,
OF NEW YORK, N. Y., A CORPORATION OF MASSACHUSETTS

CIRCULAR KNITTING MACHINE

Application filed May 17, 1929. Serial No. 363,311.

This invention relates to circular knitting machines and more particularly to circular knitting machines with revolving needle cylinders and adapted to make stripes and 5 other patterns by wrapping a plating thread around selected needles only.

One object of the invention is to produce a mechanism for making such plated or wrap-around designs on any type of circular knitting machine. Another object is to so simplify and improve mechanism of this type that it can produce a greatly increased variety 10 of patterns. According to the invention the designs are put in by a plurality of striping 15 yarn fingers revolving inside the needle circle, each finger oscillating about its own pivot point, and the path of the yarn fingers intersecting the needle circle.

The invention will be shown and described 20 embodied in the well-known Scott & Williams type of seamless hosiery machine with revolving needle cylinder.

Fig. 1 is a front elevation partly in section taken on the line I—I of Fig. 2 of the head 25 of a machine in which one form of my invention has been embodied;

Fig. 2 is a plan view of the wrapping yarn fingers and associated elements of Fig. 1;

Fig. 3 is a development of the cam ring, 30 the arrow showing the direction of movement of the needles;

Fig. 4 is a plan view similar to Fig. 2, taken on the line IV—IV of Fig. 5, showing a modification in which the pivot points of the fingers are movable in the plate carrying the 35 fingers and the axis of the plate is concentric with the needle cylinder;

Fig. 5 is a vertical section through the modification of Fig. 4, taken on the line 40 V—V;

Fig. 6 is an elevation from the left side of the machine of the embodiment shown in Fig. 1;

Fig. 7 is a further modified form in which 45 the bobbins are located below the yarn fingers and the driving means for the fingers include a differential gear;

Fig. 8 is a plan view of the differential gear shown in Fig. 7; while

50 Fig. 9 is a front elevation similar to Fig. 1

showing the invention embodied in a machine having a dial with knitting instrumentalities, the fingers being eccentrically supported and the yarns fed from above.

As shown in the drawings the invention is 55 embodied in a circular knitting machine having a revolving needle cylinder 260, carried by a bedplate B, the needles n being independently and vertically movable in the upper end of the needle cylinder as usual. There 60 is the usual latch ring 550 over which the usual plain or ground yarns are fed over the usual throatplate 559.

Referring to the embodiment of the invention shown in Figs. 1, 2, 3 and 6, there is the 65 usual yarn shear plate 26 located inside the needle circle on a dial bracket 15 which in turn is fastened to the latch ring 550. On top of the bracket are the usual yarn cutter and clamp 609. The latch ring is pivoted on 70 a bracket 401 at the rear of the machine (Fig. 6) to permit raising of the ring and plate out of the way. Revolubly mounted in the bracket 15 eccentrically of the center of the needle cylinder is a long vertical tube 22. 75 This tube extends well above the dial bracket and on its upper end is a bobbin bracket 21 carrying the striping yarn bobbins 20. The lower end of this tube projects below the shear plate 26 and serves to carry the striping 80 yarn fingers and associated mechanism.

Fastened to the underside of the yarn shear plate is a non-revoluble cam 26 lying in a horizontal plane. Just below this cam is a 85 yarn finger bracket 23 fixed on the tube 22. The yarn fingers 24 which are to carry the striping yarns are on top of the bracket 23 each being pivoted about its own vertical center 30 located intermediate its outer end or toe 28 and inner end 29. (Fig. 2.) The tube 90 22 being eccentric to the needle circle, it will be obvious that when the tube revolves the pivots 30 of the yarn fingers revolving about their common axis take an eccentric path relatively to the needle circle. The path of oscillation of the fingers about their individual pivots is in the plane of the needle circle i. e., in a plane parallel to that described by the needle hooks when all at the same level. 95 In the machine shown in the drawings, where 100

the needles are arranged in a cylinder the plane of the needle circle is normal to the axis of the cylinder i. e., the length of the needles. The path of the fingers intersects 5 the needle circle and therefore the toes of the fingers have movement in one direction relative to the needles opposite them while the toes are outside the needle circle and relative movement in the other direction while 10 inside the needle circle. This eccentric mounting of the pivot points of the fingers combined with turn for turn revolving of the needle cylinder about its center and the fingers about their common axis gives the 15 wrapping of the yarns.

I have discovered that the entire mechanism can be much improved if the eccentric path of the yarn finger pivots is combined with an oscillation of each finger about its 20 individual pivot 30. In Figs. 1 to 3 the means to accomplish this individual oscillation comprises the above mentioned cam 25 located between the yarn shear plate 26 and the yarn finger bracket 23. The inner ends 29 of the 25 fingers meet the edge of the cam 25 at points later than their respective pivot points 30 when considered in the direction of rotation about their common axis, and consequently the fingers are at a substantial angle from 30 the radial lines with the toes of the fingers ahead of their pivot points. The inner ends of the fingers are held in contact with the relatively stationary cam 25 by springs 27 (Fig. 2). By properly shaping the cam 25 35 I increase the relative movement of the toes of the fingers along the outside of the needle circle, i. e. lower their velocity more than is occasioned by the revolution of the fingers about their common axis and thereby increase 40 the number of needles which can be wrapped with the striping yarns. Of course this dropping back of each finger while outside the needle circle is compensated for by a corresponding relative advance inside the 45 circle. In other words the fingers move to and fro once about their individual axes for each revolution about their common axis. In order to accomplish this the low point of the cam 25 is adapted to be about under a finger 50 when the latter is about to cross out over the needle circle and the high point about where the finger has crossed back inside the circle. The circumferential points at which these 55 crossings preferably take place will be set forth at a later point in the specification.

This oscillation of the yarn fingers about their individual axes not only increases the number of needles around which a yarn can be wrapped but makes it possible to decrease 60 the amount of eccentricity of the common axis of the fingers. This decrease in the amount of common eccentricity has several advantages. When the eccentricity is considerable the length of yarn from the bobbin to 65 the needle varies considerably during one

revolution of the machine and it is very hard to adjust this with a yarn take-up. With the common eccentricity reduced there is very little variation in length of yarn to be taken up. I provide small individual take-ups 35 70 on the underside of the yarn finger bracket 23. It further makes it possible to have the yarn finger circle about as large as the needle circle and therefore to put in more fingers. 75

Another novel feature of the invention is the manner of guiding the yarns. The yarns from the bobbins 20 are fed down through the hollow tube or spindle 22 past the yarn shear plate and there distributed radially through the take-ups 35 to the toes 28 of the 80 individual yarn fingers. This feeding of the yarns below the dial makes the body yarns entirely independent of the wrap around yarns and permits yarn changes which have been impossible on prior machines of this 85 general type. Furthermore this method of feeding the yarns makes it possible to build machines of this wrap around type with dials therein containing knitting instrumentalities, such for instance as shown in Fig. 9. 90

Still referring to the preferred embodiment of Figs. 1, 2, 3 and 6, the means for revolving the striping yarn fingers about their common axis will be described now. If desired one can use the ordinary mechanism used to drive the dial such for instance as that shown in the patent to C. Madaris, 1,639,522, dated Aug. 16, 1927. This comprises a vertical dial drive shaft 13 actuated from the usual main bevel gear on the main drive shaft of the machine and revolving in an open bearing sleeve 12, a bevel pinion g^4 adapted to drive a bevel pinion g^3 on the adjacent end of a horizontal shaft 14. The motion of this horizontal shaft is transmitted to the eccentric tube 22 by bevel pinions g^2 and g^1 , the latter being fastened on the tube 22 by a tenon g^5 . By these means the striping yarn fingers are revolved with the same angular speed as the needle cylinder. Substantially the same mechanism can be used with a dial machine as shown in Fig. 9, and it is also possible to produce spiral patterns by a slight change in the mechanism as shown in Figs. 7 and 8. 105

Any needle selecting means can be employed to raise above the others those needles on which it is desired to wrap the plating or striping threads, such for instance as the means shown in the patent to Ivan W. Grothey, 1,678,385, dated July 24, 1928. 110 However in Figs. 3 and 6 a suitable mechanism for achieving this selection is shown. This comprises essentially a series of selecting cams 36 operating on teeth 37 formed on the bottom of the needles below the regular operating butt 31. These teeth are in the form of saw teeth and the individual selecting cams 36 are thin and each adapted to raise the needle only a distance from one tooth to the next so that it is possible to avoid any 115 120 125 130 135

waste of space between successive teeth. The operating butt may be longer than the selecting teeth 37. It is sufficient for selecting purposes for the wrap around action to raise the 5 needle the height of one tooth. These selecting cams 36 can be operated by pivoted levers 37a which are in turn connected to the usual thrust rods 460 (Fig. 6), those thrust rods being operated from both the main pattern 10 drum 120 by cams 501 and also from the auxiliary or striping drum 19 by means of the bell crank levers 17 in a well-known manner.

The circumferential relation of the various 15 parts and the manipulation of the needles to combine the selective wrapping of the plating yarn with the ordinary functions of the machine will now be set forth. In the examples shown in the drawings, with particular reference to Figs. 2 and 3, the knitting or knocking over point is indicated by the letter K and is located shortly after the throat plate 559 over which the body or ground yarns are fed to the needles. I prefer to make the 20 eccentricity of the common axis of the yarn fingers of Figs. 1, 2 and 3 in a direction about 135° after the throatplate because with the particular cam 25 and striping yarn fingers 24 shown in the drawings this will result in 25 the toes 28 of the yarn fingers crossing out over the needle circle immediately after the knitting wave at the knocking over point. The fingers therefore return across the needle circle to the inside just prior to the point 30 marked S in Figs. 2 and 3. This point is just before the needles reach the switch cam 415 which raises out of action the group of needles which are to be idle during the making 35 of the heel or toe. The wrapping is therefore 40 completed by the time the point S is reached and the selection of the needles for wrapping therefore takes place between the knitting wave and the switch cam, the needles moving in a counter-clockwise direction in Fig. 2 and 45 in the direction of the arrow in Fig. 3.

In the ordinary machine the needles when coming out of the knitting wave are raised to the level 32 which level leaves the hooks of the needles above the tops of the nebs of 50 the sinkers, the sinkers being controlled by the outside sinker ring 300 in the usual manner. I prefer to leave the needles which are not to be wrapped with the plating yarn at a lower level, namely, level 31, as shown in 55 Fig. 3, until the wrapping of the selected needles has been accomplished. Needles whose butts are at the level 31 have the tops of their hooks just even with the tops of the nebs of the sinkers and are out of the way of the 60 wrapping yarns. The level 31 is sloped up to the level 32 just about at the point S where the yarn fingers have crossed back inside the needle circle, and the needles traveling at the level 32 then ride over the leading stitch cam 65 360, clear their latches and then take yarn

in the regular manner. The selecting cams 36 acting on the saw tooth butts 37 serve to raise the hooks of the needles far enough above the nebs of the sinkers to permit wrapping of the plating yarn around them and in 70 this manner the needles around which the stripe or design is desired are selected. It might be noted at this point that this selection can be varied within a wide range without any adjustment of the yarn finger movements because of the great number of needles around which the fingers are adapted to wrap.

When the wrap around is in action the cam 360 is lowered to the dotted position (Fig. 3) so that the latches of all the needles just clear the stitches of the body fabric. The wrap around yarn is laid around the needles over the top of the sinker nebs which prevent it from getting under the latches and being cast off instead of being drawn in the hooks as it should. This cam is raised during the heel and toe. The patent to Albert E. Page, No. 1,367,425, dated February 1, 1921, shows mechanism for manipulating this cam.

Another novel feature of the invention will be apparent when the operation of the machine during reciprocating knitting is considered. When it is desired to make the heel or toe by reciprocating knitting it is necessary, of course, that the active needles pass through the knitting cams first in one direction and then in another, and it is therefore necessary that these active needles be at the level 32 no matter from which direction they approach the knitting cams. When they are approaching the knitting cams in the rotary or forward direction the cam level 32 will raise the needles to the proper level, but with the cam surface cut back to the level 31 between the points K and S, it will be obvious that special mechanism must be provided to raise the needles so that they will pass over the stitch cam 361 when the machine is oscillating in the reverse direction. For this purpose I provide a vertically movable raising cam 33 between the stitch cam 361 and the selecting cams 36, this cam being operated by levers from a thrust rod 460, or in any other desired manner. The upper end of this cam 33 is peaked intermediate its edges as shown in Fig. 3, and when in its upper or operative position, shown in solid lines in this figure, the lower edges of this peak coincide respectively with the level 31 and the cam surface underneath the stitch cam 361. It will be obvious that when this cam is raised the active needles will be raised to the level 32 when they pass the cam no matter from which side they are coming. When retracted the highest point of this cam is at the level 31. This cam is spaced a very slight distance from the needle cylinder so that it does not contact with the selecting teeth 37. The location of the top center cam 357, the throatplate 559

carrying the yarn fingers F for the body yarns, the switch cam 415 and the widening pick or dropper 680 are also shown in Fig. 3 in order that the operation of the machine may be more easily comprehended.

The operation of the preferred embodiment of Figs. 1, 2, 3 and 6 will now be set forth. Assuming that the machine is making rotary knitting and has reached the point where it is 10 desired to make stripes the thrust rods 460 which control the selecting cams 36 drop off the main pattern drum cams 501 and release the thrust rods to the selecting action of the auxiliary pattern drum 19. The desired selecting cams 36 are moved radially inward by means on the auxiliary striping drum 19 and as the needles complete the knitting wave those having teeth opposite inserted cams are raised slightly above the level 31. The other 20 needles proceed along the cam level 31 with their hooks just even with the tops of the nebs of the sinkers while the selected needles have their hooks a short distance above the nebs. The striping yarn fingers revolving about 25 their common eccentric axis at the moment that their toes 28 are ready to cross out over the needle circle are riding on the lowest point of the stationary cam 25 and the toe of each finger as it starts across the needle circle has 30 therefore about completed its oscillation in the direction of rotation of the needles and is in its most advanced position relatively to the needle circle. As soon as it has passed through the needle circle the eccentric mounting of the pivot points of the yarn fingers coupled with the increasing height of the cam 25 over the inner end 29 of the yarn finger causes 35 the cam to drop back along the circumference of the needle circle past a large number 40 of needles. The oscillation caused by the cam 25 has a component of movement along the circumference of the needle circle and therefore when the toe of the yarn finger crosses back inside the needle circle about the point S 45 the retarding oscillation due to the eccentricity of the common axis will have been increased and the toe will have been further retarded than would have been the case if the finger were not pivotally mounted. The 50 movement of the toe of the yarn finger relatively to the needle is a complete oscillation in the course of one revolution of the needle cylinder, thus wrapping the yarns completely around the needles. As the yarn fingers cross 55 back inside the needle circle at the point S the needles which were not wrapped ride up from cam level 31 to cam level 32 and all the needles will take the body yarns from the regular yarn fingers F in the throat plate riding 60 over the leading stitch cam 360 and under the top center cam 357 and the stitch cam 361. This continues until the machine is approaching the heel. On the last circular course before the first oscillation in the reverse direction at the heel the switch cam 415 is lowered 65

into action and raises the long butt needles out of action in the usual manner. About the same time the raising cam 33 is moved to its uppermost or operative position and commences to raise the needle butts to the level 70 32. It is raised in time to be in operation when the leading short butt needle passes on the last movement in the forward direction. The machine continues to revolve in this direction until all the short butt needles have 75 been raised to the level 32.

When any needles are at the level 32 their upper ends are on a level with the striping yarn fingers and it is one of the novel features of the invention that interference between the needles and yarn fingers at this time is avoided automatically without any movement of the fingers out of operative relation. During the last revolution in the forward direction the toes of the yarn fingers are crossing back inside the needle circle at the point S and as they come out at the knocking over point K after the short butt needles have already been raised by cam 33 and the long butts by the switch 415 and therefore the fingers contact with the backs of the shanks of both the long and short butt needles. Each finger automatically disposes itself out of the way until rotary knitting is resumed by pivoting about its center 30 against the pressure 90 of its spring 27. This pivoting allows the toe 28 to stay inside the needle circle, and the toe is made broad, blunt and with curved corners to avoid jamming or catching and to allow the finger to roll on the needles. The 100 fingers maintain their position without jamming during both the reverse and forward strokes.

At the end of the heel the cam 33 is lowered to its inoperative position as shown in dotted lines in Fig. 3. As the needles start coming from under the stitch cam after the last oscillation in the reverse direction they are raised only to the level 31 which leaves 105 their hooks below the striping yarn fingers and those yarn fingers can therefore pass out over the needles and resume their wrapping of threads around the selective needles.

The knitting of the remainder of the stocking will be obvious from the description already given, the successive stockings being knit as stringwork if desired. The cam 33 can be left up at the end of the toe of one stocking and as far into the next stocking as it is desired to prevent striping. This same manipulation can be availed of to stop and start the striping at any desired points in the stocking.

In Figs. 4 and 5 is shown an embodiment of the invention in which the tube 22 is concentric with the center of the needle cylinder. However the fingers are still given a culvilinear path about the center of the needle circle which intersects the needle circle. This camming movement in the plane of the needle 125 130

circle is obtained by giving the pivot points a radially sliding movement. Such part of the radial motion as was obtained from the eccentricity of the tube 22 in Figs. 1, 2 and 5, 3, is obtained in Figs. 4 and 5 by mounting the pivots 30 in radial slots 38 and extending the upper ends of the pivots into an eccentric groove 39 in a lower face of the stationary cam 25'.

- 10 A preferred form of driving means for the dial is shown in Figs. 1 and 6. The means are actuated from the main drive shaft as in the Madaris patent above mentioned but on the upper end of the vertical shaft 13 there is a horizontal sprocket wheel 40 instead of the bevel pinion g^4 . This sprocket drives a chain 41 geared to a sprocket wheel 45 on the pivot shaft 552 of the latch ring 550 by bevel pinions 43, 44, and a sprocket 42. The sprocket wheel 45 is in turn connected to the usual horizontal shaft 14 by a chain 46 and a sprocket wheel 47 on the shaft 14. It will be obvious that the yarn fingers and dial cannot get out of time with the cylinder.

25 Where in the claims I speak of "dial" it should be understood as including either a yarn shear plate or a dial having knitting instrumentalities such as transfers.

30 A considerable amount of spiralling or shogging of the pattern can be accomplished by simply varying the selection of needles in the groups which the fingers wrap but if this is not sufficient then the fingers can be shogged by the following mechanism. This can be accomplished by the mechanism shown in Figs. 7 and 8 where a differential gear is introduced into the driving means for the dial and the yarn fingers are therefore shogged slightly every revolution relatively

35 to the needles.

The vertical shaft 48 which takes the place of shaft 13 in Figs. 1, 2 and 3, carries a horizontal bevel gear 49. There is a companion gear 50 facing gear 49 and the two are connected by bevel pinions 51 and 52 revolving as usual on a frictionally held ring 53. On the outside of the ring are two rows of teeth 54 adapted to be engaged by pawls 55 and 55a. As long as the pawls 55, 55a do not rack the

40 ring 53 around the companion gear 50 will revolve in unison with gear 49 and the driving stub 56 on the gear 50 will transmit the same number of rotations. However gear 50 revolves in the opposite direction to gear 49 and therefore a reversing gear 57 is provided between the differential gear and usual pinions g^4, g^8 .

45 When the pawls 55, 55a rack the ring 53 then the companion gear 50 gains or loses a little relatively to the gear 49 according to which direction the ring is turned, and as a result the yarn fingers are shogged relatively to the needle cylinder. When both of these pawls are disengaged from the ratchet so that

50 gear the direction of the pattern formed by the wrapping threads will be in vertical lines straight down the hose, but if these pawls are made to engage the teeth of the ratchet so as to move the differential gear the direction of the pattern made by the wrapping threads will be shifted from its vertical direction on the hose either to one side or the other according to the direction in which the ratchet is moved. To give a zigzag effect 55 to this wrapping pattern the pawl on one side of the ratchet will engage the teeth of the ratchet for a given number of courses and then this pawl will be released and the other pawl will engage the teeth on the other side 60 of the ratchet and thus reverse the lateral movement of the pattern in making the zigzag effect. Any suitable mechanism can be used to actuate the pawls from the main shaft of the machine and to control them from the 65 pattern drum. For an example see the patent to Henshall, 386,819, dated July 31, 1888.

70 Fig. 7 also shows another modification of the invention in that the striping yarn bobbins are shown mounted below the yarn shear plate 26. The bobbins 58 are mounted horizontally one below the other on an axis concentric with the common axis of the yarn fingers these bobbins being carried in a shell 59, and through openings in these walls the 75 yarns are fed to the yarn fingers. This shell is pivoted on a horizontal axis at its lower end in order to make the bobbins available for manipulation by swinging the shell laterally. The bracket on which this pivotal 80 mounting is made comprises a yoke 60 having hinges 61 in each leg at a point between the upper and lower ends of the yoke. The upper ends of the yoke are rigidly fastened to the yarn finger bracket 23 and therefore 85 the bracket and shell revolve with the yarn fingers. The hinges 61 assist in making it possible to get at the various bobbins and change them as needed. The bobbins are sufficiently small to leave room around the shell 90 and the yoke for the knitted stocking to pass down through the tube and with the bobbins mounted in the manner above described it is also possible to raise the latch ring and remove the bobbins from the tube.

95 An embodiment of the invention in such a machine having a dial D with knitting instrumentalities therein, by means of an eccentric tube 22a, 100 it is necessary to provide driving means not only for the tube 22 which carries the striping yarn fingers but also for the rotating dial itself. In the drawings these driving means are shown as comprising a vertical 105

110 machine for a dial with knitting instrumentalities therein, by means of an eccentric tube 22a, 115 it is necessary to provide driving means not only for the tube 22 which carries the striping yarn fingers but also for the rotating dial itself. In the drawings these driving means are shown as comprising a vertical 120

drive shaft 13a in the semi-circular housing or sleeve 12 referred to in Figs. 1, 2 and 3, and the usual bevel pinion g^4 meshing with a bevel pinion g^3 on the end of the horizontal dial shaft 14. This horizontal dial shaft is carried by a bracket 16a which in turn is mounted on the latch ring 550 as heretofore. The end of the horizontal shaft 14 which is located over the needle circle has the usual bevel pinion g^2 meshing with a horizontal bevel pinion g^1 . This bevel pinion g^1 has a tenon g^5 taking into a slot cut longitudinally in a sleeve 62, the sleeve 62 therefore revolving with the pinion. On the lower end of this sleeve is fastened the dial proper and on top of the dial proper the dial cover and the yarn cutter and clamp as usual. This sleeve 62 is concentric with the needle cylinder and revolves in unison therewith. The vertical drive shaft 13a which drives the dial mechanism extends some little distance above the bevel pinion g^1 in order to provide means for driving the striping yarn fingers about their axis. These means include a bevel pinion 63 meshing with a vertical bevel pinion 64 in the manner of g^4 and g^3 , and a horizontal shaft 65 carrying on its opposite end pinion 66. Pinion 66 meshes with pinion 67 which latter is held from vertical movement by an arm of the main dial bracket 16a. The eccentric tube 22a revolves with the pinion 67 and carries the striping yarn finger bracket 23 as usual. The tube 22a passes down from the pinion 67 through a non-revolute eccentric sleeve 68 which fills the space between the eccentric tube 22a and the concentric sleeve 62 of the dial. This eccentric sleeve 68 is vertically adjustable by means of the usual mechanism such as shown in Fig. 14 of the above-mentioned Scott Patent 1,641,101. The screw 69 keeps the eccentric sleeve 68 from revolving.

Numerous modifications will doubtless occur to those skilled in the art, which do not depart from the scope of my invention.

I claim:

1. A circular knitting machine having a revolving needle cylinder, striping yarn fingers revolutely mounted within said cylinder, each finger also having its own individual pivot, means to oscillate each finger about its own pivot and means adapted to give said individual pivots a camming movement in the plane of and relative to the needle circle, the path of the feeding ends of said yarn fingers intersecting the needle circle.

2. A circular knitting machine having a revolving needle cylinder, a spindle eccentrically located within the needle cylinder, striping yarn fingers supported from said spindle and moving turn for turn with the needles in such a way that the path of the feeding ends of the fingers intersects the needle circle, in combination with means adapted to oscillate said feeding ends of the fingers

in the plane of the needle circle while inside and outside of the needle circle in such timed relation as to give said yarn fingers an increased movement along the outside of the needle circle.

3. A circular knitting machine having a revolving needle cylinder, a spindle eccentrically located within the needle cylinder, and striping yarn fingers pivotally supported from said spindle, their pivot points moving turn for turn with the needle cylinder and their feeding ends being adapted to intersect the needle circle, in combination with a cam adapted to oscillate the feeding ends of said yarn fingers along the needle circle to vary their travel outside of the needle circle.

4. A circular knitting machine having a revolving needle cylinder, a spindle eccentrically located within said needle cylinder, and a plurality of striping yarn fingers supported by said spindle said fingers presenting curved surfaces at their outer ends, in combination with spring means pressing the curved surfaces of said fingers yieldingly outward.

5. A circular knitting machine having a revolving needle cylinder, and independent needles therein, in combination with a pivoted yarn finger revolutely mounted within said cylinder, the pivot point of said finger having a curvilinear path around the center of the needle circle and the path of the toe of the finger crossing said needle circle, said toe being adapted to stay within the circle upon contacting with the needles.

6. A circular knitting machine having a revolving needle cylinder, a spindle eccentrically located within the needle cylinder, and a plurality of striping yarn fingers supported by said spindle in such a way that the path of the feeding ends of the fingers intersects the needle circle, the feeding end of one of said fingers being on a different radial line from the spindle than the pivot point of the finger at the moment of crossing the needle circle outwardly, in combination with spring means attached to each finger permitting the finger to yield when its feeding end meets a needle.

7. A circular knitting machine having a revolving needle cylinder, a spindle eccentrically located within the needle cylinder and revolving in unison therewith, and a plurality of striping yarn fingers pivotally supported by said spindle in such manner that their path intersects the needle circle, in combination with a relatively stationary cam adapted to give an oscillatory movement to the feeding ends of said yarn fingers to increase the number of needles wrapped thereby, and a spring tending to hold a yarn finger against said cam and adapted to permit said finger to yield radially inward when it contacts with a needle.

8. A circular knitting machine having a

revolving needle cylinder, a spindle eccentrically located within said needle cylinder and a plurality of striping yarn fingers pivotally carried by said spindle in such a way that their path intersects the needle circle, in combination with relatively stationary cam means for said fingers adapted to maintain said fingers at a substantial angle from a radial direction and by varying that angle from the radial position to vary the velocity of the feeding ends of the yarn fingers relative to the needles.

9. A circular knitting machine having a revolving needle cylinder, a spindle eccentrically located within said needle cylinder, striping yarn fingers moving turn for turn with the needles in such a way that the path of the feeding ends of the fingers intersects the needle circle, individual vertical pivots for said fingers supported by said spindle in combination with relatively stationary cam means acting on the inner ends of said yarn fingers to successively make the speed of the feeding ends of the yarn fingers, relative to the needles, less and more than the speed occasioned by the eccentricity of the spindle.

10. A circular knitting machine having a revolving needle cylinder, a spindle eccentrically located within said needle cylinder, and a plurality of striping yarn fingers pivotally supported by said spindle moving in the same direction as the needles in such a way that the path of the feeding ends of the fingers intersects the needle circle, in combination with a cam holding the inner ends of said fingers circumferentially forward of their pivot points viewed in the direction of rotation of the fingers and giving to the feeding ends of the fingers an oscillatory component of movement in the plane of the needle circle, the feeding ends describing a closed curvilinear path around a group of needles.

11. A circular knitting machine having a revolving needle cylinder, a spindle eccentrically located within the needle cylinder and a plurality of striping yarn fingers pivotally supported by said spindle moving in the same direction as the needles in such a way that the path of the feeding ends of the fingers intersects the needle circle, in combination with a cam holding the inner ends of said fingers circumferentially forward of their pivot points viewed in the direction of rotation of the fingers and giving to the feeding ends of the fingers an oscillatory component of movement adding to the number of needles wrapped by the component due to eccentricity of the spindle.

12. A circular knitting machine having a revolving needle cylinder, and a plurality of striping yarn fingers within said cylinder, in combination with means of supporting and revolving said yarn fingers in unison with said needle cylinder and a relatively non-revolvble cam cooperating with said mount-

ing means to give said yarn fingers a motion having reciprocatory components across said needle circle and back and also along the circumference of the needle circle.

13. A circular knitting machine having a revolving needle cylinder, independent needles therein, and a dial within said cylinder, in combination with a plurality of striping yarn fingers revolvably mounted underneath said dial. 70 75

14. A circular knitting machine having a revolving needle cylinder, a series of bobbins mounted above said cylinder on an axis substantially concentric therewith, and a dial in combination with a tube also substantially concentric adapted to lead yarns from said bobbins to a position below said dial, and a series of striping yarn fingers below said dial adapted to feed said yarns to the needles. 80

15. A circular knitting machine having a revolving needle cylinder, and striping yarn fingers mounted within said cylinder, in combination with means adapted to rotate said fingers at the same angular speed as the needles, and a differential gear adapted to vary the speed of rotation of said fingers, the path of the feeding ends of the fingers intersecting the needle circle. 85 90

16. A circular knitting machine having a revolving needle cylinder, striping yarn fingers mounted within said cylinder, individual pivots for said fingers and means for revolving said yarn fingers in unison with the needles, said means giving the individual pivots of the fingers a path eccentric to the needle circle, in combination with means adapted to oscillate the fingers about their individual pivot points in the plane of the needle circle. 95 100

17. A circular knitting machine having a revolving needle cylinder, striping yarn fingers revolvably mounted within said cylinder, each finger also having its own individual pivot, means to oscillate each finger about its own pivot and means adapted to give said individual pivots a radial movement, said oscillation about and movements of the individual pivots being in the plane of the needle circle, the path of the feeding ends of said yarn fingers intersecting the needle circle. 105 110 115

18. A circular knitting machine having a revolving needle cylinder, striping yarn fingers mounted within said cylinder, individual pivots for said fingers and means for revolving said yarn fingers in unison with the needles, said means giving the individual pivots of the fingers a path eccentric to the needle circle, in combination with means adapted to vary the travel of the feeding ends of the fingers in the plane of the needle circle from that occasioned by the radial positions of the feeding ends. 120

19. A circular knitting machine having a revolving needle cylinder, striping yarn fingers revolvably mounted within said cylinder. 125 130

der, each finger also having its own individual pivot, means to oscillate each finger about its own pivot, and cam means adapted to give the individual pivots a path eccentric to the 5 needle circle, the path of the feeding ends of the yarn fingers intersecting the needle circle.

20. A circular knitting machine having a revolving needle cylinder with independent 10 needles therein and striping yarn fingers mounted within said cylinder, in combination with means adapted to rotate said fingers at the same angular speed as the needles, and a differential gear adapted to displace the 15 fingers with relation to the needles for pattern purposes, the path of the feeding ends of the yarn fingers intersecting the needle circle.

21. A circular knitting machine having a 20 revolving needle cylinder and a plurality of striping yarn fingers, means for revolving said yarn fingers about a common center within the cylinder, said means giving the fingers a path eccentric to the needle circle, the feeding 25 ends of the fingers intersecting the needle circle, in combination with means pressing said fingers outwardly but permitting one or more to yield upon contact with a needle and to remain within the circle.

30. 22. A circular knitting machine having a revolving needle cylinder, yarn fingers, individual pivots for said fingers and means for revolving said yarn fingers in unison with the needles about a common center within the 35 cylinder, said means giving the individual pivots of the fingers a path eccentric to the needle circle, in combination with means adapted to oscillate the fingers about their individual pivot points in the plane of the 40 needle circle, the path of the feeding ends of the fingers intersecting the needle circle and means pressing said fingers outwardly but permitting same to turn yieldingly about their individual pivots upon contact with a 45 needle and to remain within the circle.

23. A circular knitting machine having a revolving needle cylinder, yarn fingers, individual pivots for said fingers and means for revolving said yarn fingers in unison with the needles about a common center within the 50 cylinder, said means giving the individual pivots of the fingers a path eccentric to the needle circle, in combination with means adapted to oscillate the fingers about their individual pivot points in the plane of the 55 needle circle, the path of the feeding ends of the fingers intersecting the needle circle.

24. A circular knitting machine having a revolving needle cylinder, independent 60 needles therein, a revolving dial above said cylinder and dial needles therein, pivoted wrapping yarn fingers and a bracket for said fingers revolving in unison with said cylinder and dial, in combination with spindles carrying 65 said dial and bracket and revolving same

in unison with the needle cylinder, stationary cam means to actuate said dial needles and yarn fingers, and tube means adapted to feed yarn to said fingers through said dial and bracket.

25. A circular knitting machine having a revolving needle cylinder, a stationary bracket above said cylinder, a hollow spindle in this bracket, driving means for rotating said spindle in unison with the cylinder, a 70 non-revolvble hollow shaft inside said spindle and a support for said shaft above said spindle rotating means, in combination with a shaft within said hollow shaft, rotating means for said shaft located above the non-revolvble hollow shaft, and members 75 cooperating with the cylinder needles and means actuating said members, said last mentioned means and members being carried by said spindle and shafts, there being an opening 80 within the inner shaft adapted to permit passage of a wrapping yarn from above the rotating means of said inner shaft to a position below the members cooperating with the cylinder needles.

In testimony whereof I have signed my name to this specification.

JAMES L. GETAZ.
